UNITED STATES PATENT OFFICE.

EDWARD KARFIOL, OF BROOKLYN, NEW YORK.

DESIGN FOR A DOILY.

Application filed November 23, 1928. Serial No. 28,988. Term of patent 14 years.

To all whom it may concern:

Be it known that I, EDWARD KARFIOL, a citizen of the United States, residing in Brooklyn, in the county of Kings and State of New York, have invented a new, original, and ornamental Design for Doily, of which the following is a specification, reference being made to the accompanying drawing, forming part thereof, in which—

The figure represents a face view of a doily showing my new design. The full lines of the drawing shows one quarter of the design in detail and the full line about the circumference is a continuation of the border, the dotted angular lines are a continuation of the outline of the inner portion of the doily.

I claim:

The ornamental design for a doily as shown and described.

EDWARD KARFIOL.
